UNITED STATES PATENT OFFICE.

GEORGE W. SHIEBLER, OF BROOKLYN, NEW YORK.

DESIGN FOR A SPOON.

SPECIFICATION forming part of Design No. 24,734, dated October 8, 1895.

Application filed August 15, 1895. Serial No. 559,426. Term of patent 7 years.

To all whom it may concern:

Be it known that I, GEORGE W. SHIEBLER, a citizen of the United States, residing at Brooklyn, in the county of Kings and State of New York, have invented and produced a new and original Design for the Handles of Spoons, Forks, &c., of which the following is a specification, reference being had to the accompanying drawings, in which—

Figure 1 is a plan of the obverse side, and Fig. 2 is a plan of the reverse side of a spoon or fork handle.

The leading feature of my design for the handle of a spoon or fork consists of the shell ornaments in relief upon the obverse and reverse sides at the end of the handle, combined with the adjacent scroll and leaflet ornaments in relief, as shown. Upon the obverse side of the handle, *b* represents the shell ornaments at the end of the handle, and *a* represents the adjacent scroll, and *c* the leaflet ornaments.

Upon the reverse side of the handle, *e* represents the shell ornaments at the end of the handle, and *d* represents the adjacent scroll, and *f* the leaflet ornaments. These ornaments are in relief upon the surfaces.

What I claim is—

1. The design for the handle of a spoon or fork, as set forth.
2. In the design for the handle of a spoon or fork, the design of the obverse side of the handle, as set forth.
3. In the design for the handle of a spoon or fork, the design of the reverse side of the handle, as set forth.

Signed by me this 12th day of August, A. D. 1895.

GEO. W. SHIEBLER.
